UNITED STATES PATENT OFFICE.

ALBERT KOMP, OF NEW YORK, N. Y.

IMPROVEMENT IN NECK-TIES.

Specification forming part of Letters Patent No. **157,612**, dated December 8, 1874; application filed October 21, 1874.

To all whom it may concern:

Be it known that I, ALBERT KOMP, of the city, county, and State of New York, have invented a certain new and useful Improvement in Neck-Ties, of which the following is a specification:

This invention is illustrated in the accompanying drawing, in which—

Figure 1 represents a front view. Fig. 2 is a transverse section in the plane $x x$, Fig. 1.

Similar letters indicate corresponding parts.

This invention consists of a bow, the shield of which is cut out of pasteboard or other similar material, to correspond to the shape of the side pieces, and covered with one piece of silk, satin, or other suitable material, the central part of which is stiffened by a backing of paper or other suitable material, and folded under or embossed to form an imitation cross-piece, thereby producing a bow which is handsome in appearance, easily manufactured, and durable.

In the drawing, the letter A designates the shield of my bow, which is cut out of pasteboard, card-board, or other suitable material, with wings $a a$, which correspond in shape to the side pieces of a bow of the ordinary construction. This shield is covered with a sheet, b, of silk, satin, or other suitable material, the edges of which are drawn over the edges of the shield, and fastened on its back by suitable cement. A lining, c, of muslin or other suitable material, conceals the edges of the covering material, and assists in retaining the same firmly in position. The central portion of the covering material is strengthened by a lining, d, of paper, which is attached thereto by a suitable cement, and which imparts to the same the required stiffness. The cement which I use, by preference, is gutta-percha in sheets.

By means of this stiffening I am enabled to form on the covering material, during the operation of applying it to the shield, two folds, $e e$, and I can emboss that portion situated be-

tween these two folds, so that by the central part of the covering an imitation cross-piece is produced, and thereby the appearance of my neck-tie is materially improved.

The side pieces of my neck-tie or bow are stiff and not liable to curl up; and the imitation cross-piece has the appearance of the cross-piece of an ordinary bow, and it can be produced with less labor and material than required for the production of a separate cross-piece, such as used in the manufacture of ordinary bows.

The elastic loop, f, which serves to secure my bow to the collar-stud, is fastened in the shield A in any desirable manner. In the example shown in the drawing the shield is provided with two holes, the upper hole being large enough to allow the knot, g of said loop to pass, so that when the loop is drawn through both holes the knot will catch at the inner edges of the lower hole, and the loop is firmly retained in position.

It is obvious that my bow can be made in various shapes by changing the form of the shield and that of the imitation cross-piece.

What I claim as new, and desire to secure by Letters Patent, is—

The shield A, formed with the wings $a a$, and provided with the sheet b of silk or other material overlapping the edges of the shield, with the lining covering and concealing the edges of the sheet b, and the lining d of paper for strengthening the central portion of the material, the said parts being pressed to form the two folds $e e$, and the whole being constructed and arranged substantially as and for the purpose described.

In testimony that I claim the foregoing I have hereunto set my hand and seal this 16th day of October, 1874.

A. KOMP. [L. S.]
